(57) CLAIM

The ornamental design for a light fixture ornament, as shown and described.

DESCRIPTION

This application is related to commonly assigned, concurrently filed U.S. design patent applications Ser. No. 29/197,423, Ser. No. 29/197,425, Ser. No. 29/197,426 and Ser. No. 29/197,424.

FIG. 1 is a perspective view of the light fixture ornament of the present design;

FIG. 2 is a front elevation view thereof;

FIG. 3 is a side elevation view thereof; the other side being a mirror image thereof;

FIG. 4 is a back elevational view thereof;

FIG. 5 is a top plan view thereof; and,

FIG. 6 is a bottom plan view thereof.

The broken lines shown are for illustrative purposes only and form no part of the claimed design.
